Primary Examiner — Philip S Hyder(74) *Attorney, Agent, or Firm* — Boyle Fredrickson, S.C.(57) **CLAIM**

The ornamental design of a tool handle, as shown and described.

DESCRIPTION

FIG. 1 is an isometric view of a third embodiment of a tool handle incorporating our new design, wherein the portions illustrated in dotted lines form no part of the claimed design; FIG. 2 is a front elevation view thereof; the rear elevation view being a mirror image thereof;

FIG. 3 is a right side elevation view thereof, the left side elevation view being a mirror image thereof;

FIG. 4 is a top plan view thereof; and,

FIG. 5 is a bottom plan view thereof.
